UNITED STATES PATENT OFFICE.

GRANT LEEPER, OF MEDORA, IOWA.

CORN-PLANTER.

SPECIFICATION forming part of Letters Patent No. 311,766, dated February 3, 1885.

Application filed April 15, 1884. (No model.)

To all whom it may concern:

Be it known that I, GRANT LEEPER, a citizen of the United States, residing at Medora, in the county of Warren and State of Iowa, 5 have invented a new and useful Corn-Planter, of which the following is a specification, reference being had to the accompanying drawings.

My invention relates to corn-planters, and 10 it has for its object to provide improved means for actuating the dropping mechanism.

A further object of the invention is to provide a corn-planter with improved means for dropping the corn.

15 A further object of the invention is to provide improved means for throwing the slide-actuating mechanism into and out of gear with the carrying-wheels by which said actuating mechanism is operated.

20 A further object of the invention is to provide a planter which shall be simple in its construction, durable in its use, and one that will readily and effectually drop the seed at the required intervals.

25 With these ends in view the invention consists in the improved construction and combinations of parts hereinafter fully described, and pointed out in the claims.

In the drawings, Figure 1 is a perspective 30 view of a corn-planter constructed in accordance with my invention. Fig. 2 is a plan view of the same. Fig. 3 is a transverse section through the corn-boxes. Fig. 4 is a transverse section taken through the carrying-wheels, and showing the actuating mechanism located on the shaft thereof. Fig. 5 is a detail view of the actuating mechanism located on the carrying-shaft, and Fig. 6 is a detail view of the cut-off.

35 In the accompanying drawings, in which like letters refer to corresponding parts in the several figures, A represents the carrying-frame, which consists of two longitudinal beams, B, braced at suitable points by means of cross-beams a , and carrying upon one of these cross-beams a the seat b .

40 C represents the axle, having carrying-wheels C', which are adapted to be engaged by a cross-beam, C², which slides in recesses 45 in the ends of the beams B, which are covered by means of metal plates a'. This brake-beam is operated by means of a rod, a², which passes

through an opening in the seat-supporting standard, its end being bent in order that it may be readily operated by pressure of the 55 foot.

Upon the forward ends of the beams B is provided a beam, B', the ends of which are reduced and have bearing in the upper forward ends of the runners B². These runners B² are suitably braced at their forward ends 60 by means of a cross-beam, b', and at their rear upper ends by means of two cross-beams, b². Secured between these beams b² at their upper ends are uprights b³, which are connected 65 at their lower ends to the shoes B². The runners are further braced by means of beams b⁴, which are secured to the forward cross-beam of the runners at one end and to the beams b² at their other ends.

Upon the uprights b³ and upon the cross-beams b² are provided boxes for containing the corn to be planted, which are provided on their inner sides with an opening, for the passage of the corn, and cut-offs, as will be described.

D represents metal plates or slides, which are adapted to work in the boxes containing the corn to be planted, the said slides having openings which intermittently open and close 80 the said openings of the corn-boxes. These slides are connected at their inner ends by means of a rod, d, and are provided with a notched or recessed portion within the box. The uprights upon which the corn-boxes are 85 located are made hollow, and communicate with said boxes.

Upon the rear sides of the uprights b³ are provided metal plates d', the upper ends of which rest within the notched portion of the 90 slides, and their lower ends are adapted to close openings in the uprights b³, near the lower ends thereof. It will thus be seen that as the bar to which the slides are secured is actuated the said slides will move back and forth, and in this manner operate the said plates to open and close the openings in the uprights, thus permitting the dropping of the corn at the proper intervals.

Upon the outer sides of the seed-boxes are 95 provided what might be called "bell-crank levers" d², the center portion of which is hinged to the said seed-boxes and their lower ends secured to the slides. The upper ends

of these levers d^4 are bent rearwardly at right angles to the body portion of said levers, and as the slides are actuated the same cause said levers to rise and descend, the outward movement of the slides causing the levers to rise, and the backward or inward movement of the said slides causing the upper arm of said levers to be lowered. Upon one of these levers rests a marker, (according to the direction in which the planter is planting,) secured loosely at its rear end upon a plate or bracket secured upon the rear side of the seed-boxes. It will thus be seen that as the slides are actuated the marker is caused to intermittently rise and descend to mark the ground for the hills next to be planted.

Secured upon the rear of the beams b^2 is a lever or double lever, E, the arms e of which are pivoted at about their center to brackets secured upon the inner sides of the beams B at suitable points thereon. These arms e are connected at their rear ends by means of a cross-rod, by which the runners may be raised from the ground and held in that position while the machine is being transported from place to place.

Just above the axle of the carrying-wheels are provided brackets E', which are provided near their upper ends with openings, in which openings are mounted the reduced portion of a rod or shaft, E². By this reduced portion shoulders are formed whereby the lateral movement of the said bar or shaft is limited. The outer ends of this bar or shaft E² are beveled or cut off diagonally, as shown. At about the center of this bar or shaft E² is a recessed portion, at which point is provided a headed pin or bolt, upon which is a plate, E³, having a longitudinal slot. This plate E³ is also provided at about its center with a longitudinal slot, which works upon a headed pin or bolt secured to the under side of one of the bracing-beams a of the beams B, and is hinged at its lower or front end to the bar to which the slides are connected.

It will be seen that by forming the connecting-plate with slots and mounting the same upon headed pins that the movement of the runners in passing over uneven ground is accommodated, and all jerking and strain avoided. The axle C is preferably square, and is journaled in brackets depending from the under sides of the beams B. The point at which the axle is journaled in the brackets is reduced and made rounding in order to allow of its proper revolution. The axle is also reduced and made rounding at its ends in order to receive the carrying-wheels.

Upon the inner sides of the carrying-wheels are secured, to the hubs thereof, blocks which project upwardly and are secured at their upper ends to one of the spokes. Upon the outer ends of these blocks are pivoted pawls F', which are held in position by means of springs F².

G represents a collar or disk, which is mounted on the carrying-axle adjacent to the

inner sides of the wheels, and revolves with said axle, or the axle is revolved thereby, the disk being provided with a circumferential series of teeth, which are engaged by the spring-pressed pivoted pawls upon the inner sides of the carrying-wheels.

Adjacent to the collars or disks G, and mounted within an eccentrically-recessed portion of the shaft C, are pinion-wheels G', which are connected by means of a rod, G², which passes through openings in the side of the depending blocks in which the axle is mounted, and rests in an opening in said axle. It will thus be seen that only a portion of these pinion-wheels are exposed. Inclosing the exposed portion of said pinions and the axle at the point where said pinions are located is a collar, H, provided on its inner side with a series of teeth adapted to engage said pinion-wheels, by which means said collars are revolved. These collars H are provided with tappets H', which are beveled or cut off on their inner sides to engage the beveled portion of the shaft E², and operate the said shaft intermittently, one of the tappets occupying a position directly below the axle while the other one is engaging the beveled portion of said shaft, from which it will be seen that the said shaft is automatically moved backward and forward to open and close the slides.

The ring G is provided on its inner side with teeth G³, which are engaged by the teeth of a disk rigidly mounted on the shaft adjacent thereto, which aids in holding collar G upon the teeth of the pinion-wheel, and prevent its disengagement therefrom.

The disk G² is provided with a groove or recess on its peripheral edge, which is adapted to receive a U-shaped arm or a lever, H², the upper portion or handle of which is pivoted between the arms of a bracket secured upon one of the bracing-beams a of the beams B. By this arrangement it will be seen that when disk G² is shifted from engagement with the ring or collar G, the said ring or collar will not move the seed-slides, inasmuch as they are not braced laterally, and therefore work loosely, so that in transporting the planter from place to place the actuating mechanism is not operated.

The operation of the above-described machine may be briefly mentioned as follows: The corn is placed in the hoppers or boxes and the marker adjusted as described, so that at each movement of the slides it is raised and lowered to mark the hills. The pivoted pawls upon the carrying-wheels engage the toothed disk adjacent thereto, which imparts motion to the shaft, which shaft turns the pinion-wheels and the disks G², which in turn operate the collar G, the tappet of said collar striking the beveled shaft which operates the slides.

It will be seen from the above description that by the use of my improved machine the necessity of a check-rower is obviated, and that the mechanism for operating the slides

and the marker is thoroughly efficient and effective.

Having fully described my invention, what I claim as new, and desire to secure by Letters Patent, is—

The combination, with a squared shaft carrying toothed disks adjacent to the carrying-wheels, said carrying-wheels having pivoted pawls to engage said disks, pinions mounted in recessed portions of the shaft at each end thereof, a collar provided on its inner edge with a series of teeth to engage said pinions, a shaft journaled above the supporting-frame and connected with the seed-slides, tappets 15 formed integral with said collars, a disk

loosely mounted on said shaft and provided on its inner side with teeth to engage a corresponding series of teeth on the inner side of the collar, and levers adapted to engage the latter-mentioned disk to throw the same into 20 and out of gear with said collar, substantially as set forth.

In testimony that I claim the foregoing as my own I have hereunto affixed my signature in presence of two witnesses.

GRANT LEEPER.
